UNITED STATES PATENT OFFICE.

CURTIS C. LILLIBRIDGE, OF HUTCHINSON, KANSAS.

HOT-AIR STOVE.

1,378,043.

Specification of Letters Patent. Patented May 17, 1921.

Application filed November 3, 1919. Serial No. 335,367.

To all whom it may concern:

Be it known that I, CURTIS C. LILLIBRIDGE, a citizen of the United States, residing at Hutchinson, in the county of Reno and State of Kansas, have invented certain new and useful Improvements in Hot-Air Stoves; and I do declare the following to be a full, clear, and exact description of the invention, such as will enable others skilled in the art to which it appertains to make and use the same.

This invention relates to improvements in hot air heating stoves, and it has more particular reference to a stove which is designed to use liquid fuel, although any other fuel may be used equally as well.

The principal object of the invention is to increase the heating capacity of the stove by the employment of a novel arrangement of heat absorbing and radiating surfaces within the combustion chamber of the stove, whereby cold air passing into the stove will be thoroughly heated before its passage out of the stove and into the room or other place to be heated.

A further object of the invention is to provide means carried by the hot air circulating pipe and disposed adjacent the smoke outlet, which serves to prevent rapid escape of the products of combustion through the smoke pipe and also retains the products of combustion in contact with the air pipe and more thoroughly heats it.

In the accompanying drawings forming a part of this application and in which like numerals are employed to designate like parts throughout the same,

Figure 1 is a central vertical section of a heating stove equipped with my improved devices.

Fig. 2 is a transverse section on the plane of the line 2—2 of Fig. 1.

Fig. 3 is a like view on the plane of the line 3—3 of Fig. 1.

In the drawings I have shown a heating stove S equipped with a liquid fuel burner B such as disclosed in my co-pending application filed November 3, 1919, Serial No. 335,369, and also equipped with automatic cut off mechanism C such as disclosed in my U. S. Patent 1,334,251 of March 16, 1920.

The stove S includes a vertical casing having an air inlet opening 1 in its side wall, which is preferably disposed a little below the center of its height, and it is also provided at its top with a hot air outlet

opening 2 which is preferably disposed near the center of the stove. It is also provided with the usual smoke outlet opening D above the air inlet 1. Inclining upwardly from the opening 1 and communicating with the opening 2 at the top is an air circulating pipe or flue 3 which is of approximately the same diameter throughout its length. At the back of the stove a concave shell 4 is cast integral or otherwise secured thereto, its upper end being closed and covering the opening 1, and its lower end being open and disposed adjacent the floor, as illustrated. With this construction it will be seen that air rising from the floor will pass upwardly through the shell coming into contact with the casing of the stove, thereby becoming partially heated before its passage through the flue 3, wherein it is highly heated before its passage out of the openings 5 into the room. Such heating of the air is due to the fact that the flue 3 is disposed within the combustion chamber of the stove and is exposed partially to the flames and excessive heat from the burner B which thoroughly heats it, consequently heating the air that passes through it. Preferably cast integral with the pipe 3 and arranged at spaced intervals entirely around it are a plurality of heat absorbing ribs or fins 6 which serve an important part of this invention. That is, these ribs project outwardly from the surface of the flue and are in close proximity to the flames of the burner B and the rising flames will be held in the space between the ribs, thereby being retained in direct contact with the flue from its bottom to its top and more effectively heating the flue and the air which passes therethrough. These ribs not only serve to retain the flames in effective contact with the pipe 3, but they themselves become red hot, and absorb a great amount of heat and transmit it to the interior of the flue to superheat the air which passes therethrough. Hence, it will be seen that this construction greatly increases the exterior heating surface of flue and absorbs the heat from the fire more rapidly than if otherwise constructed. It is to be noticed that these ribs are arranged on the exterior surface of the flue and they do not in any way decrease or interfere with the free passage of air through the flue.

I have found that in heating stoves of the ordinary construction, a great amount of

heat is wasted, due to the fact that it passes out through the smoke flue. I have provided means to prevent, as much as possible, rapid escape of the particles of combustion. 5 To this end I provide an oppositely tapered short fin 7 which is also cast integral with the pipe 3 and is disposed adjacent to the rear wall of the casing. A heat deflecting plate 8 rests on the top edge of fin 7 and 10 partially surrounds the pipe 3. As shown, the plate 8 is preferably disposed adjacent the smoke outlet D and it is provided with a slot 9 which is of a length to extend beyond the opposite sides of the fin. This slot 15 9 serves to permit a retarded passage of the products of combustion therethrough. Most of the particles of combustion rising from the burner B will be caught beneath the deflecting plate or baffle 8 and will very gradually escape to the smoke flue through the 20 opening 9 and around the outer edges of said plate. Hence, it will be seen that rapid escape of the products of combustion will be prevented, as the baffle 8 will form a pocket 25 and tend to deflect and retard the flow of a portion of the products of combustion. This plate will also tend to keep the fin 7 red hot at all times. In order to secure this baffle 30 8 in place I provide it with an upturned flange 10 which rests against the inner surface of the wall of the stove casing and which is secured thereto in a manner as will hereinafter be described.

The fuel supply tank 11 is supported by 35 means of an outwardly extending shelf 12 which is provided on its inner end with a downturned flange 13 which bears against the outer surface of the stove casing wall. Bolts 14 are passed through the flanges 10

and 13 and through the casing wall, thereby 40 retaining the plate 8 and shelf 12 in position. The shelf 12 is supported by means of a brace 15.

Inasmuch as a stove of this character and construction becomes very hot, I have found 45 it advisable to afford protection for the tank 11 which may otherwise become over-heated and explode so I attach a suitable shield 16 to the shelf 12 between the tank and the body of the stove and this shield prevents 50 the tank from becoming excessively heated, as is obvious.

I claim:

A stove comprising a vertical cylindrical casing having an air inlet opening in its 55 side wall, a hot air outlet opening in its top and a smoke outlet opening in said side wall above said air inlet opening, a hot air circulating pipe in the casing extending upwardly at an incline from said air inlet opening to said hot air outlet opening and provided on its exterior with longitudinally extending fins, an additional downwardly tapered fin carried by said hot air pipe in the angle between the same and the casing 60 wall and forming a support having a horizontal upper end, and a horizontal deflecting plate carried by said fin and extending between the wall and pipe and resting upon the upper end of the supporting fin and 65 curved to conform to the contour of the wall and the adjacent part of the hot air pipe, said plate being provided with a slot extending beyond the sides of the supporting fin to provide an auxiliary air passage. 70 75

In testimony whereof I have hereunto set my hand.

CURTIS C. LILLIBRIDGE.
